CLAIM

I claim the ornamental design for a lid, as shown and described.

DESCRIPTION

FIG. 1 is a top plan view of the lid;

FIG. 2 is a bottom plan view thereof;

FIG. 3 is a front side view thereof;

FIG. 4 is a rear side view thereof;

FIG. 5 is a left side elevational view thereof;

FIG. 6 is a right side elevational view thereof; and,

FIG. 7 is a perspective view thereof.

The broken lines in the drawings depict portions off the lid that form no part of the claimed design.
